VISOR CAP

Constance Bannister and Mario Petitta, New York, N. Y.

Application May 20, 1957, Serial No. 660,101

2 Claims. (Cl. 2—195)

This invention relates broadly to the head covering arts and in its more specific aspects it relates to hats or caps which are provided with a visor or other generally lateral projection from the head band or body thereof and means preventing the pressure of the wind or resistance of the air from causing the cap or hat from being blown from the head of the wearer; and the nature and objects of the invention will be readily recognized and understood by those skilled in the arts to which it relates in the light of the following explanation and detailed description of the accompanying drawings illustrating what we at present believe to be preferred embodiments or mechanical expressions of our invention from among various other forms, arrangements, combinations and constructions, of which the invention is capable within the spirit and scope thereof.

While we have illustrated and shall describe our invention as applied to the sun or glare visor of a cap it is to be distinctly understood that it may be applied to the brim or any other projection from the body of a hat or head covering or to a conventional eye shade and still fall within the spirit and scope of our invention.

It is well known that many types of caps having sun or glare preventing visors projecting therefrom are awkward and inconvenient to wear when the wind is blowing or the wearer is riding in a vehicle or the like so there is substantial resistance to the movement by the air. The awkwardness or inconvenience is caused by wind pressure or air resistance being generated beneath the visor with sufficient intensity to produce upward movement on the visor to cause the cap to be lifted from the head of the wearer. When the intensity of the wind or resistance of the air is of a force sufficient to remove the cap the wearer must either hold it on his head, or if possible to pull it so tightly that it causes discomfort or take it off and hold it. Every wearer of caps and others will readily appreciate that the cap fails to serve a useful purpose if it is affected by wind and air resistance. As far as we are aware no one prior to now has attacked and solved this problem as we have by providing means incorporated in the visor for automatically releasing wind pressure and air resistance beneath a visor or the like projection from a head covering to thereby prevent such pressures and resistances from blowing the cap from the head of the user.

The primary function of a visor on a cap is to keep the sun and glare from the eyes of the wearer. Hence in evolving our visor it has been necessary to incorporate the pressure and release means therewith in such a manner that the visor will continue to serve its prime function, i. e., the elimination of sun and glare from the eyes of the wearer. We have been able to provide visor mounted pressure and resistance release means without sacrificing the necessary glare and sunlight prevention attributes of the visor.

The provision of pressure and resistance release means on a visor as devised by us has not detracted from the

2

appearance of the hat, cap or the like nor has it weakened the visor in any manner whatsoever.

With the increased use of visor caps for wear by players of a multitude of sports and by millions of others whose work or recreation is out of doors or in other areas affected by wind pressures and/or air resistance it will be recognized that there has long been a need for some practical and efficient means for preventing pressures and resistances from building up beneath the visor of a cap or the projection of a hat or under an eye shade or the like with sufficient force to blow the cap, hat or the like from the head of the wearer.

By the invention about to be described we have satisfied this long felt need by devising a visor providing ingenious pressure and release means which does not detract from the appearance of the hat or cap and does not adversely affect the glare preventing characteristics of the conventional visor.

We have accomplished this highly advantageous result without sacrificing economy of production or the lasting qualities of a conventional visor.

With the foregoing general objects, features and results in view, as well as certain others which will be apparent from the following explanation, the invention consists in certain novel features in design, construction, mounting and combination of elements, as will be more fully and particularly referred to and specified hereinafter.

Referring to the accompanying drawings:

Fig. 1 is a top plan view of a visor cap provided with our pressure and resistance release means.

Fig. 2 is a side elevational view of the visor cap of Fig. 1.

Fig. 3 is a fragmentary view of the ends of a pair of slats or panels forming a part of our pressure and resistance release means.

Fig. 4 is a fragmentary view in perspective of a modified form of slot or panel and mounting means therefor.

Fig. 5 is a view in perspective of the visor cap of a further modified form.

In the accompanying drawings, we have used the numeral 1 to designate the crown or body of a cap or the like head covering. This crown while illustrated as being made of light, flexible fabric material may, of course, be made of any appropriate material and may if desired be of helmet type, that is it may be hard and rigid. The cap may include the usual head band 3 which may be of any suitable and desirable type. We have used the numeral 5 to designate generally the visor 50 which is attached to the front portion of the body of the cap to project forwardly therefrom to protect the eyes of the wearer from sun and glare.

The visor 5 is preferably formed of relatively rigid material which is light in weight such as plastic, light weight metal as aluminum or any other material having the necessary characteristics and capable of performing the functions for which the visor has been designed. The visor may constitute a solid body which is formed to provide the pressure and resistance release means as will be explained and is of visor or elongated shape the outer perimeter of which is arcuate while the inner perimeter extends into the body of the visor, is arcuate and conforms generally to the curvature of the outer perimeter. The outer perimeter of the visor comprises what we shall term an "outer rim" providing oppositely disposed sections 7 and a forward section 9. The inner perimeter of the visor comprises what we shall term an "inner rim" 11, the outer and inner rims being joined at their rear ends as at 13.

The visor is formed by stamping, extrusion or in any other suitable manner to provide a plurality of transversely extended slats or panels 15 which extend between

the sections 7 of the outer rim. While we have disclosed the slats 15 as being an integral part of the visor and integral with the outer rim sections it is to be recognized that they may comprise separate elements which are fixed to and extend between the outer rim sections. Each slat 15 is provided with a supporting portion 17 at its rear end which extends between the sections 7 of the rim and is integrally formed therewith or may be connected thereto in any suitable manner. Extending forwardly and downwardly from said supporting portion 17 of each slat or panel is a vane 19 providing a reaction surface as will be hereinafter explained in detail. As will be apparent from consideration of the drawings each vane 19 extends below the visor and is of course angularly related to the plane thereof and is not in abutment with or connected to the rim sections 7. Thus a series of transverse slots are formed in the visor, each such slot extending between each vane and the next forwardly adjacent supporting section 17.

Adjacent the rear end of the visor where the inner rim 11 extends between sections 7 of the outer rim we may provide reduced length slats 21 which extend between rim 11 and the adjacent section 7, each of such slats also being formed with the supporting section 23 and the downwardly and forwardly depending vane 25.

The visor 5 is adapted to be fixed to a cap body 1 in the following manner. At its inner edge the inner rim 11 is formed with an upstanding flange 27 having a series of spaced holes 29 therealong. The visor may be fixed to the cap by stitching passing through the holes 29 in the flange and a band 31 may be provided to cover the flange and to more securely fix the visor to the cap. The band may be sewed to the cap and this stitching may also pass through the apertures in the flange.

In Fig. 5 of the drawings we have illustrated a further method by which the visor of this invention may be attached to a cap and in this instance the visor is removably attached to the cap. The visor is formed as in the form of the invention illustrated in Fig. 1 of the drawings with the flange 27 having the apertures 29 therethrough. To this flange we sew or otherwise attach a band 33 provided with any suitable number of snap fastener elements 35 adapted to be removably fastened to complementary fastener elements which are fixed to the cap 1. Thus each visor includes the band 33 affixed to the flange so that a visor may at will be attached to and detached from a cap.

In Fig. 4 of the drawings we have illustrated a further form of our invention. In this form of invention we have provided a plurality of slats 37 which extend between the rim sections and are pivotally mounted therein. Each slat 37 is provided with a pivot pin 39 projecting from each transverse edge thereof and the rim sections are provided with holes 41 in which the pins 39

are journaled with sufficient friction to prevent the slats from flapping therein. Thus when wind pressures on air resistance builds up the wearer need only pivot the flaps 37 downwardly to provide the slots in the visor to form release vents for the pressures and resistances beneath the visor.

It will now be readily apparent that the vanes of the slots form reaction surfaces against which wind pressure and air resistance will act as the air flows upwardly through the slots or vents in the visor to thereby release pressure and resistance and in acting on these vanes will generate a downward reaction on the vanes, the visor and hence the cap to thereby aid in preventing its blowing from the head of the wearer. Hence, the vanes function in a dual capacity, both as a release means for pressure and resistance and as a reaction means for holding the head covering on the head of the wearer.

We claim:

1. A cap visor comprising a rim providing oppositely disposed sections, a plurality of slats extending across said visor and between said rim sections and each slat including a supporting section fixed to and extending between said rim sections, a vane fixed to and extending downwardly and forwardly from the forward edge of each supporting section providing a slot through the visor above each vane, said vanes providing reaction surfaces to direct air through the slots relieving pressure beneath the visor and providing a downward force on the visor.
2. A cap visor comprising a plurality of longitudinally spaced slats extending transversely across the visor providing a plurality of longitudinally spaced transverse slots through the visor, a rigid vane fixed to each slat and extending downwardly and forwardly therefrom under a slot and said vanes forming reaction surfaces to direct air through the slots to generate a downward force on the visor.
